UNITED STATES PATENT OFFICE.

EDGAR C. LAKEY, OF PROVIDENCE, RHODE ISLAND, ASSIGNOR TO B. A. BALLOU & CO.
INC., OF PROVIDENCE, RHODE ISLAND, A CORPORATION OF RHODE ISLAND.

BUTTON.

1,346,660.

Specification of Letters Patent. Patented July 13, 1920.

Application filed April 10, 1920. Serial No. 372,834.

To all whom it may concern:

Be it known that I, EDGAR C. LAKEY, a citizen of the United States, and resident of the city of Providence, in the county of Providence and State of Rhode Island, have invented certain new and useful Improvements in Buttons, of which the following is a specification.

This invention relates to improvements in the construction of buttons more particularly cuff buttons and the like, and the object of this invention is to provide a button with an improved form of eye or loop member connected to the back thereof which is much stronger than the ordinary loop or eye.

A further object of this invention is in addition to providing a strong and durable loop or eye for the back of a button to be able to also reduce the cost of construction of such a button when formed of precious metal.

The nature and advantages of the invention will be better understood when the following detail description is taken in connection with the accompanying drawings, the invention residing in the combination and arrangement of parts as claimed.

In the drawings forming part of this specification, like numerals of reference indicate similar parts in the several views and wherein:—

Figure 1 is a side elevation illustrating a button having my improved form of eye or loop member on the back thereof.

Fig. 2 is a plan view showing the loop blank as cut from sheet stock.

Fig. 3 illustrates the center portion of the loop blank as bent up into loop form from the plane of the ends thereof.

Fig. 4 is a perspective view of the back-plate of the button, removed.

Fig. 5 is a perspective view of the filler member for the interior of the button.

Fig. 6 is a central sectional view illustrating the members in assembled position.

With reference to the drawings, 10 designates the front plate of the button, which may be made of any suitable material, but which is usually cut and formed from sheet material and 11 designates the back-plate 50 of the button which is provided with a central hole or opening 12 therethrough, which back-plate is secured to the front plate by rolling the edge 13 of the front plate over that of the back plate.

My invention comprises essentially the

construction of the eye-member 14 and the manner in which it is applied to the button.

The eye-member itself is preferably formed from sheet stock in the shape best illustrated in Fig. 2, in which is shown the end portions 15 of the eye-member as being wider or considerably enlarged over the middle or loop portion 16 thereof. The middle or loop portion is then bent up as illustrated in Fig. 3 into loop form, which loop portion is 65 passed through the opening 12 of the back-plate 11, the ends of feet portion 15 of the loop being arranged to extend laterally in opposite directions and lie flat against the inner side of the back-plate and between it 70 and the back of the front-plate.

It will be seen by this construction that where the ends of the loop are made broader or larger than the loop opening 12 in the back-plate that these enlarged portions serve 75 as anchors or retaining members beneath the back-plate, to positively prevent the loop ends from being drawn through this opening.

In assembling the parts I preferably provide an annular ring 17 having a central 80 opening 18 of a size to fit around the outside of the feet member 15 of the loop thereby providing means for taking up the space between the front and back plates not occupied by the ends or feet of said loop, which ring 85 also serves as a stiffener for the front-plate.

When the parts of this button are all formed of precious metal, it will be noted that by my improved construction both the front and back plates may be made of extremely thin stock while the loop member, which is called upon to withstand the greatest amount of strain, may be formed of a stock several times as thick as that of either the back or the front plates. In this way the 95 ends of the link member 19 are turned inwardly into this loop member and a strong and durable button is thus provided being constructed of very thin solid precious metal.

Another feature of this construction is 100 that no solder whatever is employed in the construction of this button and therefore the stock remains hard, not having been annealed or softened by the application of heat, which would necessarily be the case when a soldering operation has been performed.

My improved construction of button is extremely simple, practical and effective in its operation.

The foregoing description is directed 110

solely toward the construction illustrated, but I desire it to be understood that I reserve the privilege of resorting to all the mechanical changes to which the device is susceptible, the invention being defined and limited only by the terms of the appended claims.

I claim:

1. In a button, a front-plate, a back-plate secured to said front-plate and provided with a central opening through it, a loop member formed of sheet stock and having its middle portion bent outwardly into loop form, with said loop portion extending through said back-plate opening, the ends of said loop extending laterally beneath said plate providing anchors for said loop.
- 10 2. In a button, a front-plate, a back-plate secured to said front-plate and provided with an opening through it, a loop member formed of sheet stock and having its middle

portion bent outwardly into loop form and extending through said back plate opening, the end portions of said loop being enlarged over the loop strip providing enlarged foot portions extending laterally beneath said back to secure the loop in position.

3. In a button, a front-plate, a back-plate secured to said front-plate and provided with a central opening through it, a loop member formed of sheetstock and having its middle portion bent outwardly into loop form and extending through said back-plate opening, the ends of said loop extending laterally beneath said plate providing anchors for said loop, and a filler member taking up the space between said back and front plates not occupied by the ends of said loop.

In testimony whereof I affix my signature. 40

EDGAR C. LAKEY.
